UNITED STATES PATENT OFFICE.

GEORGE F. HUTCHINS, OF WORCESTER, MASSACHUSETTS, ASSIGNOR TO THE KNOWLES LOOM WORKS, OF SAME PLACE.

TAKE-UP MECHANISM FOR LOOMS.

SPECIFICATION forming part of Letters Patent No. 380,117, dated March 27, 1888.

Application filed July 8, 1887. Serial No. 243,736. (No model.)

To all whom it may concern:

Be it known that I, GEORGE F. HUTCHINS, a citizen of the United States, residing at Worcester, in the county of Worcester and State of Massachusetts, have invented certain new and useful Improvements in Take-Up Mechanism for Looms; and I do hereby declare that the following is a full, clear, and exact description thereof, which, in connection with the drawings making a part of this specification, will enable others skilled in the art to which my invention belongs to make and use the same.

My invention relates to variable take-up mechanism for looms in which the speed or degree of movement of the take-up roll is varied by means of a shield governing the movement given to a ratchet-wheel by a push or pull pawl.

The object of my invention is to produce an improved take-up mechanism for looms, and to provide a simple mechanism by means of which a great range of speeds of the take-up roll upon which the woven fabric is wound is obtained without resort to changing the gears in the train, through the intervention of which the take-up roll is operated, and also to provide for particular advantages in fancy weaving by operating the push or pull pawl directly from the Jacquard or harness-head motion.

Referring to the drawings, Figure 1 is a side view of a portion of an ordinary loom, showing the application of my invention. Fig. 2 is an end view of some of the parts shown in Fig. 1. Fig. 3 is a modified detail of the locking mechanism shown in Figs. 1 and 2, to be hereinafter described.

In the accompanying drawings, A is the loom-frame.

b is a ratchet-wheel, cast upon the hub of which is the pinion b'. A stud, b², is secured to the frame A, upon which the ratchet-wheel b and pinion b' turn. The gear c, which is fast upon the shaft c', which turns in a bearing, c², secured to the loom-frame A, meshes with the pinion b'. The shaft c' projects through the bearing c² and carries upon its inner end pinion c³, which engages with the gear-wheel d, secured upon the end of the

take-up roll d', which has its bearing in the stand d², secured to the frame A. (See Fig. 2.) The arm e has its bearing upon the stud b², and is provided with a shield or guard, e' e², at its outer end, which projects over and covers 55 part of the teeth of the ratchet-wheel b.

The forward part or end, e², of the shield or guard e' e² is attached by a hinged joint, e³, to the part e', making of the part e² of the shield or guard e' e² the holdfast-pawl of the ratchet. 60 It will thus be seen that the jointed shield or guard e' e² does away with the separate holdfast-pawl and stand. The outer end or part, e², of the shield e' e² is shown elevated by dotted lines, Fig. 1. Said part is held down upon 65 the ratchet-wheel b in all positions by means of the flat spring e⁴. The part e² is so shaped as to guide the push-pawl smoothly into the ratchet-teeth, with no liability of the pawl rebounding and jumping the tooth, as might be 70 the case in quick running, with the shield up clear of the teeth, so the pawl must drop over its edge.

Upon the same hub with arm e is cast an arm, e⁵, to the end of which is jointed the nut 75 e⁶, leaving the nut free to turn in the direction of the plane of the arm. Into the nut e⁶ is screwed the lower end of the rod f, which has a bearing in the stand f', fast to the frame A.

Upon the upper end of the rod f, just above 80 the bearing, is secured a small hand-wheel, f², which, with a collar, f⁴, fast on rod f just below the bearing, holds said rod in position, so that when the rod is turned the nut e⁶ is raised or lowered, according to the direction of motion of the rod f, which has the effect of swinging the shield or guard e' e² in one direction or the other relatively to the teeth of the ratchet-wheel b. In this instance a lock-plate, 85 f³, of any ordinary construction, (with its interior edge cut out to correspond with the hexagonal-shaped hub of the hand-wheel f² and adapted to fit over said hub,) is secured by a screw, f⁶, to the bearing of the rod f. By turning out the screw f⁶ the lock-plate f³ will 90 be drawn out and away from the hexagonal hub on the hand-wheel f², allowing said hand-wheel and the rod f to be freely turned in either direction; and by turning in said screw f⁶ the lock-plate f³ will be drawn in to engage 95

100

and fit over the hexagonal hub of the hand-wheel and prevent the rod f from being turned in either direction as long as the lock-plate engages the hub of the hand-wheel.

5 It will be understood that I do not limit myself to the special way of locking the rod f to prevent it from being turned shown in the drawings, for any ordinary way may be employed; and it is not essential that the rod f should be locked, for the object of locking the rod is simply to prevent the weaver from changing the take-up after it is once set.

The front end of the push-pawl g is placed above the shield or guard $e' e^2$. The back end 15 of the pawl g is in this instance pivoted to the arm g' , which arm is fast upon one end of the shaft g^2 , which has a bearing in the stand g^3 , bolted to the frame A. (See Fig. 1.) Upon the inner end of the shaft g^2 is fastened the 20 arm g^4 , to the end of which is attached the connection g^6 to the Jacquard or harness-head motion, according to the character of the loom to which my take-up mechanism is applied.

A coiled spring, g^5 , secured at one end to the 25 frame A and at the other end to the arm g^4 , draws said arm g^4 into the position shown in Fig. 1 when released by the Jacquard or harness-head motion. In the stand g^3 are supported stops g^7 , to regulate the degree of motion 30 of the arm g^4 .

The operation of the take-up mechanism described and shown in the drawings is as follows: The parts being in the position shown in Fig. 1, motion is given to the push-pawl g , through the arms $g' g^4$, by means of the Jacquard or harness-head motion, through the connection g^6 . The pawl g slides over the outer end, e^2 , of the shield or guard $e' e^2$ until it strikes the root of the first tooth of the 40 ratchet-wheel b not covered by said shield, and for the remainder of its motion the ratchet-wheel b , and through the gearing train above described the cloth-roll d , are turned in the proper direction to take up the woven fabric 45 coming over the breast-beam B of the loom. By loosening the lock-plate f^3 and turning the rod f the operator can swing the shield $e' e^2$ so that a greater or less number of teeth will be exposed to the action of the pawl g , so that a 50 greater or less proportion of the given movement of the pawl will act to move the take-up roll.

It will readily be seen by those skilled in the art that the closeness of regulation of the 55 take-up in this manner is limited by the fineness of the ratchet-wheel teeth. If it is desired to regulate the take-up finer than this, the shield $e' e^2$ can be set so as to permit the pawl g to take twice as many teeth plus one 60 as were before exposed to the action of the pawl. If, then, the harness motion is changed so as to give motion to the pawl only on every second pick of the loom, the effect will be to split a tooth on the ratchet-wheel. Instead of 65 taking twice as many teeth plus one, twice as many plus two or three might be taken, or

three times as many plus two or three and the harness motion set to every third pick, so that the take-up can be varied to any degree of fineness and still have no changing of gears in 70 the train, and have the ratchet-wheel with teeth large and strong, subject to no danger of breakage.

It is often desirable in fancy-weaving to stop the take-up on certain picks—as, for instance 75 for weaving a flower or figure which is superimposed or floated upon a ground, when it is desirable to take up only on ground picks. My invention enables me to do this perfectly, as the cords of the Jacquard can be so punched 80 or the harness-chain so made as to call the action of the pawl g , operated by the Jacquard or harness motion, at will.

The push-pawl for operating the ratchet-wheel may be operated by means of a crank, 85 h^2 , on the end of the bottom shaft, h^3 , instead of by means of the Jacquard or harness-head motion, as above described; or the pawl may be operated from the lay of the loom.

The pawl g may be arranged to pull in- 90 stead of push, if preferred, in which case the teeth of the ratchet-wheel will be reversed.

The amount of motion given to the pawl g for a given travel of the harness motion can be varied by leaving the connection g^6 more 95 or less slack, and a yielding spring, g^5 , may be made use of to advantage.

It is sometimes desirable to wind the woven fabric directly upon the take-up roll, in which case it is necessary to make the take-up roll 100 revolve slower as the woven fabric accumulates thereon, or it will take up too fast.

In Fig. 3 I have shown a form of lock designed to allow the weaver to shift the shield or guard $e' e^2$ by turning the rod f so as to expose a less and less number of teeth as the woven fabric accumulates on the take-up roll. In said figure, f^3 is a stand; f^2 , the hand-wheel; f^4 , the collar; and f^5 is a second hand-wheel threaded upon the hub of the hand-wheel f^2 , so that by screwing down the hand-wheel f^5 upon the stand f^3 the rod f is held in position.

Having thus described my invention, what I claim as new, and desire to secure by Letters 115 Patent, is—

1. In a take-up mechanism, the combination, with a ratchet-wheel and a push or pull pawl for operating the same and means for operating said pawl, of a jointed or hinged shield or guard, the outer end of which acts as a holdfast-pawl, substantially as described.

2. In a take-up mechanism, the combination, with a ratchet-wheel and a push or pull pawl for operating the same and means for 125 operating said pawl, of the movable jointed shield or guard, the shield-support, a jointed nut attached to said support, a screw-rod connected with said nut for adjusting said shield or guard, and means for supporting said rod, 130 substantially as set forth.

3. In a loom, the combination, with a

ratchet-wheel for driving the take-up roll and an adjustable jointed or hinged shield, the outer end of which acts as a holdfast-pawl, and means for adjusting said shield, of a push or pull pawl and connections intervening between said pawl and the Jacquard or harness motion for actuating the same, substantially as shown and described.

4. A jointed or hinged shield or guard for an actuating push or pull pawl, the outer end of which shield acts as a holdfast-pawl, substantially as and for the purpose stated.

GEORGE F. HUTCHINS.
